UNITED STATES PATENT OFFICE.

JAMES D. MORRISON, OF REINBECK, IOWA.

WELL-DRILLING DEVICE.

1,338,460.

Specification of Letters Patent. Patented Apr. 27, 1920.

Application filed August 22, 1919. Serial No. 319,170.

To all whom it may concern:

Be it known that I, JAMES D. MORRISON, a citizen of the United States of America, and a resident of Reinbeck, Grundy county,

5 Iowa, have invented certain new and useful Improvements in Well-Drilling Devices, of which the following is a specification.

10 My invention relates to improvements in rotary well drilling devices, and particularly to the means used in excavating oil and gas wells.

15 The object sought to be attained in the employment of my improved device is to secure reliable indications of the presence 15 of oil or gas bearing strata while being traversed by the boring-tools, in advance of the administration by the device of sealing material to the porous wall of the well-bore.

20 I have accomplished the above object by the means which are hereinafter described and claimed, and which are illustrated in the accompanying drawings, in which Figure 1 is a central vertical longitudinal 25 section of a well-borer containing my improved drilling-device also in like section, with parts of both broken away; Fig. 2 is a horizontal cross-section of the outer tubular conduit and the contained tubular filter 30 of the device, and Fig. 3 is a perspective view of the main or follower boring-tool.

In said drawings, similar numerals of reference refer to similar parts throughout the several views.

35 The main boring-tool 4 of my device and its jointed sectional supporting and operating tube 1, whose sections are detachably connected by coupling-sleeves 2, are of the type in general use, the cutter-head having 40 a pair of wing-cutters 6, and the body of the head exteriorly threaded for connection by means of a threaded coupling-sleeve 3 with the lowermost section of said tube 1. The body 4 has longitudinal passages 5

45 which are positioned in advance of the cutters 6 relative to the direction of their rotation. A liquid, therefore, which is conducted under head as by a pump, into the open upper end of the rotatable tube 1, 50 traverses the passages 5, and is discharged in front of each cutter, where it sweeps the detritus of material as fast as excavated and carries it upwardly past the cutters, which are diametrically wider than said tube, and 55 through the annular interspace of the tube

and the wall of the bore 7 to the open upper end of the latter for final discharge, while there subject to inspection and examination.

As the wall of the bore 7, in different geological strata, and especially in certain 60 geographical regions, is often porous and very friable so as to quickly become permeated by and fall apart under the action of a passing stream of water, it has, in such cases, become usual and necessary 65 to fill the water pores with a finely comminuted calcareous material by pumping it under considerable head into the tube 1 while the latter is being rotated by means of suitable mechanism and a releasable rotary clamping-device not shown. Such a solution, in which the water is impregnated to its full capacity, has little or 70 no scouring or abrasive effect while passing upwardly under head along the wall of the 75 bore, but on the other hand, gives up some of its calcareous contents to the porous wall, silting up or sealing the pores in the wall for a distance and thus effectively preventing disintegration of the wall and collapse 80 of the same, filling the bore and ruining the well.

This sealing up of the porosities of the bore wall, while advantageous, is subject to the following disadvantage in the prospecting for oil, water or gas. As the boring-tool traverses such a stratum, the fine particles of calcareous substance in solution in filling the superficial pores of the bore wall, also 85 so close them as to often render them impermeable to the oil, gas or water which would otherwise issue in sufficient amount to be easily distinguishable, with the exhaust water ejected at the mouth of the bore, permitting timely steps to be taken relative 90 thereto.

95 My improved device is operable and effective for the preservation of both said useful but opposed advantages.

In my combined device, the cutter-body 100 or tool 4, hereinafter termed the follower, is preceded by a channeled cutter 12 of less diameter adapted to form an exploratory bore in advance of the excavatory action of the follower. The tool 12 has its body 10 105 exteriorly threaded to be received in the interiorly-threaded lower end of an imperforate tube 9 which is of less diameter than said bore. The channel 11 in the body 10 permits passage of water through the tool 110

and thence upwardly to the main bore 7 to be discharged with the exhaust water leaving the follower 4. The upper end of the tubular section is threaded, traversing and secured in the threaded central opening of the body to project thereabove, and is connected by a coupling-sleeve to other like sections above, within and concentrically spaced from the inner wall of the tube 1. The upper section or sections 14 of the tube 9 is closed at its upper end by a threaded stop 20, while it has numerous small perforations 15. Surrounding this perforated or foraminated part 14 is a tubular filter closely fitted therearound and comprising next the tube a netted wire cover 16, this being covered with a layer of cloth 17, and this by a covering sleeve 18 of metal provided with numerous small orifices 19.

20 In the operation of my device, when water fully impregnated with clay or the like, is forced into the rotating tube 1 under head, part of it passes by the filter without permeating it, traveling to the follower 4, and 25 thence, returning upwardly through the bore 7, depositing some of its contents in silting up the bore wall as above described. Another part, however, traverses the filter, passes down the tube 14—9, and the cutter 30 10—12, issuing and moving upwardly along the walls of the smaller bore to thence pass into the larger bore above.

As the filtered water when delivered to the tool 12, contains nothing in solution which 35 could seal up the pores in the wall of said small bore, any oil issuing is taken up and accordingly appears at the top of the well, for instant recognition. The operation of the boring device may then be stopped, but 40 if the operation is preferably continued, the whole bore above the follower will nevertheless have its wall sealed by the action of the impregnated exhaust water.

Various changes may be effected in the 45 elements and relations thereof to each other in accomplishing the aforesaid desired results, without departing from the scope of this invention.

Having described my invention, what I 50 claim as new, and desire to secure by Letters Patent, is:

1. In apparatus of the character described, longitudinally spaced rotary boring devices, each device having a passage for a liquid 55 positioned to carry the liquid to the excavating part and thence to a discharging channel, the entrances of the passages in said devices being isolated from each other.
2. In apparatus of the character described, 60 longitudinally spaced rotary boring devices of different diameters, each device having a passage for a liquid positioned to carry the liquid to the excavating part and thence to that part of the bore particularly formed 65 by said excavating part, and means for isolating the entrances of said passages in said devices from each other.

3. In apparatus of the character described, longitudinally spaced coaxial rotary boring devices of which the preceding one is of less 70 diameter than the following device, and means for carrying fluids of different character independently to said devices.

4. In apparatus of the character described, coaxial channeled rotary boring and flush- 75 ing devices positioned for differential boring operations, and detachably connected for simultaneous coaction.

5. In apparatus of the character described, coaxial channeled rotary boring devices de- 80 tachably connected for simultaneous coaction, and separated means for carrying fluids of different consistencies to said devices.

6. In apparatus of the character described, coaxial channeled rotary boring devices ar- 85 ranged to operate simultaneously in producing communicating bores of different diameters, a filter, a conduit conveying an unfiltered liquid to said filter and to the following device only and a conduit leading from 90 said filter and delivering to the preceding device only.

7. In apparatus of the character described, coaxial channeled rotary boring devices, de- 95 tachably connected, and arranged to operate simultaneously in producing communicating bores of different diameters, a filter, a conduit conveying an unfiltered liquid to said filter and to the following device only, and a conduit leading from said filter to deliver 100 to the preceding device only.

8. In apparatus of the character described, a rotatable tube, a channeled follower boring-tool removably mounted in and closing one end of said tube and also having a central opening, a channeled preceding boring-tool of less diameter coaxial with the follower boring-tool, a tubular conduit in one end of which the preceding boring-tool is removably mounted and which is secured in 110 and traverses the opening in the follower boring-tool, a tubular filter in the said rotatable tube above both boring-tools and in communication with said tubular conduit, said filter adapted to strain part of an unfiltered liquid traversing said tube toward the follower boring-tool, and to deliver the filtered liquid to said preceding boring-tool only.

9. In combination, a rotary main excavating device containing a fluid circulatory system, and an auxiliary preceding excavating device of less diameter having a fluid circulatory system, said systems being adapted to carry fluids of different character 120 separately to the excavating elements of said devices and thence to the walls of the cavities formed by the respective devices.

10. The method of treating the wall of a boring into the crust of the earth, which con- 130

sists in subjecting that part of the wall which extends a relatively short distance above the lower end of the boring while being progressively excavated to a fluid application operating to keep the porosities of that part only of the wall open, and following this operation, by progressively subjecting this treated part in the wall to a fluid application operating to close said porosities.

11. The method of treating the wall of a boring into the crust of the earth, which

consists in subjecting that part of the wall which extends a relatively short distance above the lower end of the boring while being progressively excavated to a non-pore-filling liquid, and simultaneously subjecting that part of the wall which is above said first-mentioned part to the action of a pore-filling liquid.

Signed at Waterloo, Iowa, this 19th day of August, 1919.

JAMES D. MORRISON.
